GRAIN CLEANING AND SEPARATING
MACHINE

Leonard Jones, Winnipeg, Manitoba, Canada

Application February 15, 1932, Serial No. 593,085

2 Claims. (Cl. 209—12)

The invention relates to improvements in grain cleaning and separating machines and an object of the invention is to provide a machine which can be manufactured at relatively small cost and which will effectively clean the grain passed therethrough and separate the several grains, discharging them in different locations.

A further object is to provide a machine which is particularly effective in separating wild and tame oats from other grains and which can also be used for separating wild oats from tame oats.

A still further object is to provide a machine wherein the grain in falling streams is subjected to several air blasts which carry out the lighter materials and discharge them in the blast from the machine.

A still further object is to construct a machine embodying an endless belt presenting considerable nap and which can be adjusted to any desired angular position and to associate with the belt an air blast which can be controlled in its direction and which acts to positively insure that the lighter free sliding grains will be discharged from the upper end of the belt.

25 A further object is to construct the machine so that the various air blasts can be readily controlled to insure of the most efficient operation of the machine.

A further object is to provide a novel agitator associated with the grain hopper and also reciprocated brushes associated with certain screens and acting to prevent clogging of such screens.

A further object is to provide the machine with a reciprocated shoe having upper and lower decks and with the top deck receiving grain discharged from the endless conveyor and delivering the grain in a falling stream onto the lower deck and to embody also as part of the machine structure a fan having an air trunk leading between the decks and directing a strong blast of air through the stream of grain falling from the top deck to the under deck.

With the above more important and other minor objects in view which will become more apparent as the description proceeds, the invention consists essentially in the arrangement and construction of the parts hereinafter more particularly described, reference being had to the accompanying drawings, in which,

50 Fig. 1 is a side view of the machine.

Fig. 2 is a view of the opposite side of the machine to that shown in Figure 1.

Fig. 3 is a front end view.

Fig. 4 is an enlarged detailed vertical sectional view at 4—4 Figure 3.

Fig. 5 is a horizontal sectional view at 5—5 Figure 4.

Fig. 6 is a vertical sectional view at 6—6 Figure 4.

Fig. 7 is a perspective view showing details of 60 the brush.

Fig. 8 is an enlarged detailed vertical sectional view at 8—8 Figure 1.

In the drawings like characters of reference indicate corresponding parts in the several figures. 65

The main frame of the machine is of the well known construction embodying corner legs 1 connected by suitably spaced connecting bars 2 and braced by angularly disposed brace bars 3 at opposite sides. The upper part of the frame at the 70 forward end is provided with a grain receiving hopper 4, the details of which will be later explained and rearwardly of the hopper, the frame carries a fan or blower casing 5 containing a multi-bladed rotating fan or blower 6 which is 75 mounted on the fan shaft 7, the shaft being carried in suitable bearings carried by the opposite sides of the main frame. Draught controlling gates 8 of well known design are provided on the ends of the fan casing for controlling the amount 80 of exterior air permitted to enter the casing.

The hopper embodies opposing end boards 9 carried by the main frame and front and rear downwardly converging boards 10 and 11 there between which boards feed towards the outlet 85 from the hopper in the usual manner.

The fan casing is provided with a forwardly extending air trunk generally indicated by the reference numeral 12 which underlies the hopper and comprises two similar opposing side boards 90 13 and 14 extending from the fan casing, a bottom closure plate 15 extending between the boards and a top closure plate 16 extending between the boards, the top closure plate having an inclined 95 upwardly extending wing 17 which forms a continuation of the lower edge of the hopper board 11 so that grain discharges through the outlet 4' of the hopper directly into the forepart of the air trunk 12.

Between the forward ends of the side boards of the air trunk, I locate an inclined cross board 18 and from the lower edge of this board a downwardly and rearwardly inclining cross plate 19 leads between the side boards to a point approximately midway of the length of the trunk. A 100 horizontal lying divisional board 20 extends between the rear ends of the side boards and has its front end spaced from the rear end of the plate 19 to provide a grain escape passage 21, it being here observed that the grain discharging 110

- from the hopper will be directed into the forward part of the trunk in a falling stream and will then slide down the plate 19 and escape through the passage 21 where it is caught by an endless 5 apron or conveyor later described. Directly above the cross board 20 is an adjustable wing or valve 22 which can be set in any desired position by manipulating an operating lever 23 located at the outer side of the machine. 10 It will be here observed that the board 20 divides the rear part of the trunk into upper and lower air passages and that the valve 22 is located in the upper passage. 15 The air flowing in the upper passage is directed forwardly through the stream of grain falling from the hopper and carries dust, dirt and like particles of foreign material with it, thereby effecting an initial cleaning of the grain. The air flowing through the lower passage is directed towards the upper end of the apron or endless conveyor already mentioned and later described. 20 A deflector plate 24 is secured to the forward edge of the divisional board and curves upwardly so that the blast through the upper part of the trunk is concentrated on the stream of grain in a location close to the outlet 4'. A feed controlling gate 25 is pivotally attached to the lower edge of the board 10 by a pair of parallel links 26 and 27, the link 27 being extended to provide 25 a hand lever 28. Friction of the parts is relied upon to hold this gate in any adjusted position and it will be apparent that by manipulating the handle, one can increase or diminish the extent of the feed opening 4' from the hopper. 30 In order to insure of an even and positive feed from the hopper, I have mounted an agitator in the hopper adjacent the outlet, the agitator comprising a cross bar 29 having the ends thereof slidably mounted in the ends of the hopper and the body part thereof fitted with spaced teeth 30 directed towards the outlet. Means later described is provided for reciprocating the agitator when the machine is running. 35 Underneath the air trunk, I have located an endless conveyor or apron indicated generally by the reference numeral 31. This apron embodies similar opposing side boards 32 which are pivotally swung from a cross shaft 33 suitably carried by the main frame. The upper ends of the side 40 boards are adjustably supported by similar adjusting bars 34 pivotally attached to the sides of the boards and having their upper ends longitudinally slotted as indicated at 35, the slots receiving bolts 36 carried by the ends of the hopper and fitted with adjusting nuts 37 in the well known manner. Obviously the inclination or angular position of the endless conveyor can be adjusted as desired to insure effective operation. 45 The upper ends of the side boards carry a cross shaft 38 which is mounted in any well known manner for adjustment towards or away from the shaft 33 and the shafts 33 and 38 carry similar rollers 39 which are connected by an endless belt 40 having considerable nap. The belt can be brought to the proper tension by adjusting the upper shaft. A scraper 41 underlies the upper end of the belt and has the ends thereof pivotally carried by the side boards 32 so that the scraper can rock to accommodate the belt. A discharge chute 42 is secured permanently to the side boards 32 and is adapted to receive and discharge from the machine the material discharged from the upper end of the belt. 55 At the rear edge of the plate 19, I locate a pivoted air deflector 43 which is arranged so that it can be adjusted to any desired position by manipulating an exterior handle 44. This air deflector controls the point at which the air blast through the lower part of the trunk strikes the upper end of the endless belt and is utilized for a very important purpose later explained. 60 In the lower part of the machine frame, I mount a reciprocated shoe which embodies an upper deck 45 and a lower deck 46. The frame of the lower deck is supported forwardly by spring bars 47 extending upwardly from one of the bars 2 of the main frame and rearwardly by spring bars 48 attached to the rear corner legs and to the sides of said deck. The bottom deck carries the top deck, suitably disposed side bars 49 being utilized for this purpose. The top deck is designed to receive material discharging from the lower end of the endless belt and pass the same forwardly of the machine while the bottom deck is designed to receive material from the top deck and discharge the same rearwardly. 65 The top deck embodies a rear vertically disposed cross board 50, a bottom pan 51, a gathering plate 52 above the rear end of the pan and a scalping screen 53 in advance of the plate. The forward end of the pan discharges through an outlet passage 54 provided and the grain passed through the outlet passage 54 is subsequently caught by the front end of the under deck. 70 The under deck embodies a grading screen 55 and a seed screen 55' and reciprocated brushes 56 underlying the screens and adapted to sweep the screens and prevent the same from becoming clogged when the machine is in operation. The brushes are all similar and are carried by opposing similar side bars 57 slidably carried by the sides of the frame of the under deck and provision is made for simultaneously reciprocating the side bars 57. 75 The main drive shaft 58 of the machine, which is suitably carried in bearings provided on the main frame, is provided with a driving pulley 59 and with similar eccentrics 60 which operate in the rear ends of pitmans 61 associated with the bottom deck, the arrangement being such that when the main shaft is driven by a belt 62 from an associated electric motor 63, the bottom deck and the top deck are both simultaneously reciprocated. 80 To the rear of the top deck, I locate a second fan casing 64 containing a multi-bladed fan 65 carried by the fan shaft 66 which latter is suitably mounted in side bearings carried by the machine frame. An air trunk 67 leads forwardly from the fan casing 64 in a location between the decks of the shoe and has the forward end contracted as indicated at 68 and positioned to direct a blast of air through the stream of grain discharging from the upper deck through the outlet 54 and dropping down onto the forward end of the screen 55' of the lower deck. An adjustable deflector plate 69 is provided directly opposite the outlet 68 so that one can control the direction of the blast passing through the stream of grain to best advantage. 85 The drive shaft 58 is provided at its opposite ends with similar pulleys 70, one of which through the crossed belt 71 drives a pulley 72 on the fan shaft 7 and the other of which through a belt 73 drives a pulley 74 on the conveyor shaft 33. The shaft 7 carries a further pulley 75 which is connected by a belt 76 to a pulley 77 secured to the fan shaft 66 and the shaft 33 is fitted with a chain wheel 78 which drives through an endless chain 79 a further chain wheel 80 mounted 90

a stub shaft 81 carried by one of the bars 2 of the machine frame.

To the chain wheel 80, I connect pivotally a pitman 82 which operates a crank 83 secured to 5 a cross shaft 84 rotatably carried by the front legs 1. The shaft 84 is provided with a pair of levers 85 which are connected to the side bars 57 by connecting bars 86, the arrangement being such that when the chain wheel 80 rotates, the 10 brushes are reciprocated and sweep the screens. A bell crank 87 is pivotally attached to the side of the machine frame and has one end longitudinally slotted and receiving slidably a pin 88 extending from the adjacent end of the bar 29. 15 An operating bar 89 connects the bell crank to an eccentric pin 90 carried by the chain wheel 78 and obviously according to this arrangement, when the machine is operating, the bar 29 will be reciprocated within the hopper.

20 The above completes the description of the operating parts and it will be seen that when the motor is driven, the shoe is agitated, the fans are rotated, the brushes are reciprocated, the agitator is operated and the endless belt is driven in the 25 direction indicated by the applied arrow Figure 4.

This machine is specially valuable for removing such grain seeds as wild oats or tame oats from other grains, it being known that wild oats have a considerable beard so that they have a 30 natural tendency to cling to a nap surface.

Assuming that the machine is in operation and that the mixed grains including wild oats are placed in the hopper, the action of the machine is as follows.

35 The grain in the hopper will be agitated adjacent the feed opening by the agitator and will be fed evenly and effectively through the discharge outlet therefrom depending on the amount that the gate 25 is opened. The grain falling from 40 the hopper is initially cleaned of the lighter foreign material, such as dust, chaff and light weed and grain seeds, by the blast of air passing through the upper part of the air trunk 12 and crossing such stream, the light foreign material 45 being blown out through the front end of the machine over the top of the board 18. In this connection, it will be remembered that one can adjust the valve 22 and the gates 8 in order to obtain the best regulation of air as experience 50 will dictate.

The grain, after this initial cleaning, is caught by the plate 19 and directed to the outlet 21 where it again falls in a stream onto the lower 55 end of the top side of the endless belt or carpet 40. Here a further separation is effected, the heavier and smooth grains sliding down over the belt and discharging onto the plate 52 while the lighter and bearded grains are carried up by the top side of the belt.

60 I wish it here to be particularly noted that the air blast in the lower part of the trunk 12 is directed through the grain stream and against the upper part of the endless belt, provision being made so that the direction of the blast in regard 65 to the belt can be controlled by manipulating the air deflector 43. By properly directing this blast against the belt and through the stream, I find that the lighter grains including both wild and tame oats are carried out of the stream and 70 blown forcibly against the upper end of the belt where they are held by the blast against rolling or sliding down and are consequently positively

discharged by the belt over the upper end thereof and expelled by the board 42, it being noted that the scraper clears off anything adhering.

The heavier grains falling on the lower end of the belt are separated, those not being caught in the nap sliding down and off the lower end of the belt onto the plate 52 and those caught in the nap and including wild oats and small seeds, being carried up by the belt and being delivered onto the board 42. The material caught by the plate 52 is fed forwardly onto the screen 53 which separates the heavy foreign material from the heavier grains, the foreign material travelling over the screen and being discharged at the front end of the machine and the grains going through the screen and being directed to the outlet 54 by the pan 51.

At this point, the grain falls in a further stream onto the upper end of the seed screen 55' and in falling is subjected to a further strong blast from the fan 65 which carries out any remaining lighter material. A final separation of the grains is made by the bottom deck, the small cracked wheat and weed seeds going through the forward screen 55' and any remaining small grain kernels going through the rear screen 55 and the effectively cleaned wheat being discharged from the rear end of the screen 55.

It will be particularly noted that with the construction provided, I am able to maintain an air pressure distributed over a desired area of the belt and which is used to great advantage in insuring of delivery over the upper end of the belt of certain grain. While I have shown only one deflector operating in the blast, it will of course 110 be understood that several deflector plates could be used in a larger blast to obtain the desired air pressure over a larger area of the belt.

What I claim as my invention is:—

1. In a grain cleaning and separating machine, 115 in combination, an elevated grain receiving hopper having an adjustable outlet, an inclined driven endless belt underlying the hopper, said belt presenting considerable nap, means interposed between the hopper and the belt for 120 catching the initial stream of grain discharging from the hopper and subsequently discharging it in a second falling stream directed towards the lower end of the belt, a blower, means for directing an initial cleaning blast of air from the blower 125 through the first stream of grain and leading the blast from the machine clear of the belt and means for directing a second blast of air from the blower through the second stream of grain and towards the upper end of the belt. 130

2. In a grain cleaning and separating machine, 135 in combination, an elevated grain receiving hopper provided with an adjustable outlet, an inclined endless driven belt underlying the hopper, said belt presenting considerable nap, a blower, an air trunk communicating with the blower and interposed between the hopper and the belt, said trunk being internally transversely divided to provide upper and lower blast passages and having the upper passage receiving in a falling stream the grain discharging from the hopper and discharging that grain to fall across the second passage in a stream onto the lower end of the belt and an adjustable valve for controlling the blast in the upper passage. 140

LEONARD JONES.
